UNITED STATES PATENT OFFICE.

CHARLES A. DENNEY, OF PORTLAND, INDIANA.

PALLET.

1,395,483.

Specification of Letters Patent.

Patented Nov. 1, 1921.

Application filed November 29, 1920. Serial No. 427,125.

To all whom it may concern:

Be it known that I, CHARLES A. DENNEY, a citizen of the United States, residing in the city of Portland, in the county of Jay, 5 State of Indiana, have invented certain new and useful Improvements in Pallets, of which the following is a full, clear, and comprehensive specification and exposition.

The object of this invention, broadly 10 stated, is the provision of a construction of the nature herein set forth which preferably will be formed entirely of sheet metal yet being so constructed as to afford a maximum of strength in practice and which can be 15 manufactured and sold at a comparatively low price.

Other objects and advantages of the invention will suggest themselves in the course 20 of the following description, and that which 25 is new will be set forth in the appended claims.

The preferred means for the construction 30 of this invention is shown in the accompanying drawings, in which—Figure 1 is a top plan view of my pallet complete. Fig. 2 is a bottom plan view of the same, one portion being broken away to show the construction more clearly. Fig. 3 is a central longitudinal section, as taken on the line 3—3 of Fig. 2. Fig. 4 is a cross section as taken on the line 4—4 of Fig. 2. And Fig. 5 is an enlarged detail view, as 35 taken on the line 5—5 of Fig. 4. Similar indices denote like parts throughout the several views.

In order that the construction, the operation, and the advantages of my invention 40 may be better understood and appreciated I will now take up a detailed description thereof.

My device comprises the plate 1 which, in this instance, is oblong in shape and its size and shape determines the extent of the complete pallet which may be of the shape 45 and size desired.

Contacting with the underside of the plate 1 is the grid which is made up of a plurality of ribs 2, which are substantially square in cross-section, that is they are 50 L-shaped, with the open side next to the underside of the plate 1, as shown in Fig. 3.

Said ribs 2 are spaced apart and each two, except the outer two, are connected by horizontal portions which are in contact with 55 the underside of the plate 1. In other words the entire grid is made of a single sheet

of metal bent zig-zag, each portion being of equal extent with all of the other portions and each part being at right-angles to the part next thereto, all substantially as 60 shown in Fig. 3.

The side portions 3 and 4, which are integral with the plate 1, project down at right-angles to the plate 1 and cover the ends of the grid, and then extending inward 65 from the respective portions 3 and 4 are the edges 5 and 6 which are parallel with the plate 1, spaced therefrom, and formed integral therewith.

The two supporting bars, or rails, 7 and 70 8 are L-shaped in cross section and they are located at right-angles to the ribs and are positioned near the ends thereof and extend thereacross, as shown in Fig. 4. The flanges of the bars 7 and 8 contact flat with 75 the lower surface of the ribs, and said flanges of the bars are permanently secured to each of the ribs 2 by means of rivets 9 and 10.

The ends 11 and 12 of the bars 7 and 8 80 extend upward in contact with the two outer ribs 2, to the plate 1 and then extend outward a short distance in contact therewith and then a portion 13 and 14 of the projecting ends of the plate 1 are bent inward 85 flat upon said ends of the bars 7 and 8, thereby securely locking the ends of the bars 7 and 8 to the plate 1. Also the end flanges of the ribs 2 are clamped between the portions 13 and 14 and the plate 1, all 90 substantially as shown.

By the arrangements just described it is evident that I provide a very strong and rigid pallet which can not be easily twisted or warped out of position, at the same time 95 providing a pallet which is comparatively light in weight.

The pallet above described is particularly intended for supporting clay products, such as tiling or vessels or the like, the clay 100 products being placed on the pallet when the material is in a green state, whereby it may be easily handled or carried about and finally left to dry upon the pallet.

I desire that it be understood that various changes may be made in the details of construction from that herein shown and described without departing from the spirit of the invention and without sacrificing any of the advantages thereof.

Having now fully shown and described my invention, what I claim and desire to

secure by Letters Patent of the United States is,—

1. A pallet comprising a grid, supporting bars extending across near the ends of the grid and contacting with one side thereof, a flat plate covering the other side of the grid and inclosing the edges thereof, all substantially as shown and described.
2. A pallet comprising a grid, supporting bars extending across near the ends of the grid and contacting therewith, a flat plate covering the other side of the grid, and means whereby all of said parts are securely fastened together by the material of which they are composed, all substantially as shown and described.
3. A pallet formed of sheet metal and comprising in combination a grid formed of a single sheet bent zig-zag to provide a plurality of parallel ribs, a flat sheet of material covering one side of the grid and extending over the edges thereof, and bars extending across in contact with the other side of the grid opposite to said flat sheet, and means whereby all of said parts are securely locked together by the material of which they are composed.
4. A pallet comprising a flat sheet of

metal, a grid formed of a single sheet of material bent to form ribs on which said flat sheet rests, and bars located in contact with the underside of said grid and extending at right angles to said ribs, and means for rigidly securing all of said parts together.

5. A pallet comprising a flat sheet of metal forming the top plate, a second sheet of metal bent to form a plurality of parallel ribs on which said plate may rest, the side portions of the top plate being bent to inclose the ends of the ribs, bars extending longitudinally of the underside of the ribs and in contact therewith with their ends extending upward into contact with the underside of the top plate, the ends of the top plate being bent to engage the ends of said bars, and rivets connecting said bars to the ribs, all substantially as shown and described.

In testimony whereof I have hereunto subscribed my name to this specification in the presence of two subscribing witnesses.

CHARLES A. DENNEY.
